UNITED STATES PATENT OFFICE.

AUGUST RINCKLAKE, OF BRUNSWICK, GERMANY.

LAMP-COLLAR.

SPECIFICATION forming part of Letters Patent No. 312,385, dated February 17, 1885.

Application filed February 21, 1884. (No model.) Patented in Germany January 8, 1884, No. 25,404.

To all whom it may concern:

Be it known that I, AUGUST RINCKLAKE, of 5 Brunswick, in the Empire of Germany, have invented a certain new and useful Improvement in Apparatus for Preventing Sweating of Petroleum-Lamps, of which the following is a specification.

My invention relates to improvements in lamps, especially such as are used for hydro- 10 carbon oils, in which the burner is screwed or secured within a socket or collar upon the bowl or basin; and the object of my invention is to prevent the oil from oozing through the plaster or other material by which the metal 15 collar or socket is generally fastened upon the glass bowl.

In the accompanying drawings, Figure 1 is 20 a vertical section of a lamp embodying my improvement. Fig. 2 is a vertical section of a collar or socket to be mounted upon the neck 25 of the glass bowl. Fig. 3 is the same metal collar seen from below; and Fig. 4 is a vertical section of a detail thereof, enlarged.

In carrying out my invention I arrange a 30 hollow ring or collar, *a*, upon the neck of the lamp reservoir. Said collar is screw-threaded upon its inner side to receive the burner. The upper part of the hollow ring or collar *a*, I fill with glue, gum, cork, or similar substance, 35 *b*, which is impermeable by petroleum or oil. The lower part of the hollow ring *a*, or that part which surrounds the neck of the lamp-reservoir upon its sides, I fill with plaster-of-paris or similar material, *c*, in the usual or 40 any other suitable manner. By this arrangement oil cannot ooze through the pores of the plaster.

In order to prevent any escape of petroleum along the shaft of the pinion or pinions by which the wick is raised or lowered, I have 45 arranged a shell, *d*, soldered to the burner-shell, and in the said shell *d*, I have arranged an elastic packing, *e*, which is compressed by a screw fitting into the shell *d*, and is thereby forced to bear against the pinion-shaft and 50 against its seat within the shell, thus preventing any oil from coming forth from the wick along the pinion-shaft. The said packing *e* may conveniently consist of glue properly prepared for the purpose, of rubber, cork, or 55 similar matter, preferably resisting to petroleum.

What I claim as my invention, and desire to secure by Letters Patent, is—

1. In a lamp, the combination of a lamp-reservoir having a neck or rim and a hollow collar or ring adapted to fit about said neck, and containing near its upper portion packing impermeable to oil, said collar or ring being secured to the neck or rim by plaster or 60 similar substance, substantially as specified.

2. In a lamp, the combination of a lamp-reservoir having a neck or rim, the collar or ring *a*, adapted to be secured about said neck or rim, the packing *b*, impermeable to oil, and 65 the plaster *c*, substantially as specified.

The above specification of my invention signed by me this 24th day of May, A. D. 1883.

AUGUST RINCKLAKE.
